HYDRAULIC MOVEMENT TRANSMITTING SYSTEM

Edward Roker Robertson, Middlesex, England, assignor to Simmonds Aeroaccessories Limited, London, England

Application July 15, 1944, Serial No. 543,149
In Great Britain July 23, 1943

5 Claims. (Cl. 138—30)

This invention relates to hydraulic movement transmitting or telecontrol systems which comprise a transmitter having two or more compressible liquid holding chambers, of the "Sylphon" bellows type, connected respectively with pipe lines and a receiver having two or more expansible liquid holding chambers connected with the pipe lines such that compression of a transmitting chamber causes an expansion of a corresponding receiving chamber.

In systems of the above kind it is necessary to provide compensating means which permit of the expansion and contraction of the working fluid, due to changes in temperature, without affecting the operation of the system as a whole. In one known arrangement such means comprise auxiliary "Sylphons," one for each pipe line, the movable ends of which are connected together such that while an increase in pressure in all the pipe lines will cause the "Sylphons" to expand an increase in pressure in one pipe line and a reduction in pressure in another line, such as occurs during transmission of movement, will have no effect. One example of a system of this kind is shown in U. S. Patent No. 2,168,397. Alternatively the "Sylphons" at the transmitter or at the receiver may themselves operate to provide the desired compensation. One example of this arrangement is shown in U. S. Patent No. 1,791,489 in which in a transmitter comprising two "Sylphons" the free ends of the "Sylphons" are connected to opposite ends of a pivoted link and the motion to be transmitted is applied to the pivot. Thus expansion of the fluid merely causes both "Sylphons" to expand and rotate the link about its pivot while movement of the pivot causes one "Sylphon" to expand and the other "Sylphon" to contract.

In these known hydraulic systems it has been found that if the static pressure of the operating liquid is low a sudden movement of the transmitter may reduce the pressure in one of the pipelines to a subatmospheric pressure when the liquid column in the pipe will break, thus putting the system out of action. Moreover the static pressure in the system, being due solely to the spring of the "Sylphons," may fall to a very low value as the liquid and the "Sylphons" contract at low temperatures. It has accordingly been proposed in my prior British specification No. 543,340 to provide a spring which causes the "Sylphons" of a system of the kind described in U. S. Patent No. 1,791,489 to be urged towards their compressed positions. In this arrangement although the static pressure is increased by the

operation of the spring it will still vary with expansion or contraction of the operating liquid and at low temperatures may fall to a value such that operation of the system produces a subatmospheric pressure or vacuum sufficient to break the liquid column. Moreover in this arrangement if the static pressure be raised to a suitable level at the lowest working temperature by the use of a suitable spring the pressure may 10 increase above a safe value at the highest working temperature.

It is accordingly an object of the present invention to provide an hydraulic system in which the static pressure is maintained at a suitable 15 level over the whole working temperature range.

A further object of the present invention is to provide an hydraulic system of the kind described in which the static pressure is maintained substantially constant at any temperature within 20 in the working range.

Other objects and advantages of the present invention will become apparent during the course of the following description with reference to the accompanying drawings in which—

25 Fig. 1 is a plan view of a receiver embodying the invention, and Fig. 2 is a central vertical section on the lines 2—2 of Fig. 1 looking in the direction of the arrows, certain of the elements shown in Fig. 2 not being shown in Fig. 1.

30 While the receiver illustrated forms part of a system of the kind described in U. S. Patent No. 2,168,397, that is of the kind in which additional "Sylphons" are provided for temperature compensation it will be appreciated that the invention 35 may also be applied to systems of the kind shown in U. S. Patent No. 1,791,489 in which the "Sylphons" at the transmitter or at the receiver, also act as compensating devices.

The receiver shown in Figs. 1 and 2 comprises 40 a base casting 10 having thereon upstanding apertured lugs 11 and 12 to which the heads of "Sylphon" type bellows 13 and 14 are secured by nuts 15. The bellows are connected to pipe lines 17 and 18 which extend through a flexible metallic tubing 19 to a transmitting device.

45 The movable heads of bellows 13 and 14 are connected together by means of a link 20, the centre of which is pivotally connected with a member 21 by means of a pin 22. The lower end of member 21 is pivotally mounted on a fixed pin 23 and the upper end is provided with an arcuate rack 24 having teeth engaging with a pinion 25 mounted on spindle 26. A pointer 27 (Fig. 2) movable 50 over a fixed scale 28 is secured to one end of the spindle 26. Backlash between the teeth of rack

24 and pinion 25 is prevented by a cord 29, one end of which is wrapped around the spindle 26. The other end of the cord is secured to the free end of a V-shaped spring 30, the other end of which is anchored to a pillar 36 on the base casting 10.

The temperature compensating device comprises a pair of "Sylphon" type bellows 31 and 32 mounted on lugs 33 and 34 by means of nuts 35. The movable heads of these sylphons are connected by arms 37 and 38 with opposite ends of a link 39 pivotally mounted on a fixed pin 40. The upper end of link 39 is provided with an extension 41 on which is mounted a pin 42 and a spring 43 extends between this pin and a pillar 44 mounted on the base casting 10. The compensating bellows 31 and 32 are connected with the working bellows 13 and 14 and with the pipe lines 17 and 18 by means of pipes 45 and 46 respectively.

The operation of the system is as follows. Pressure differences occurring in the pipe lines 17 and 18 due to the operation of the transmitter will cause bellows 13 to expand and bellows 14 to contract or vice versa. Such movement of the sylphons will cause the rack 24 to move to produce a corresponding movement of the pointer 27. Such pressure differences will, however, be unable to cause movement of the compensating bellows 31 and 32 since the spring 43, which urges both these bellows to a compressed position is sufficiently strong to prevent such movement for any pressure produced in the system under normal working conditions. The bellows are, however, free to expand together against the action of the spring 43 as the volume of liquid in the system increases due to an increase of the ambient temperature.

As shown in Fig. 1 the compensating bellows 31 and 32 are in the position they occupy at a mean working temperature, and the spring 43 exerts a torque on the link 39 about pin 40 to urge the bellows to their compressed position. As the working temperature increases and the bellows expand inwards the torque exerted by the spring 43 decreases since the perpendicular distance between the axis of the spring and the centre of pivot pin 40 decreases. Also the torque exerted by the spring will increase as the temperature falls. Thus the varying torque exerted by the spring supplements the effects due to the spring rate of the bellows themselves which in the absence of the spring produce a maximum static pressure in the system at the maximum working temperature and an undesirably low minimum static pressure at the minimum temperature. By suitably balancing the effects of the spring in relation to the spring rate of the bellows the static pressure in the system, over a desired temperature range, may be maintained substantially constant and, if desired, at a relatively high value, e. g., 100 lbs. $\square'$ such that the instantaneous pressures developed during reasonable operation of the system can never at any

temperature develop subatmospheric pressures tending to produce a breakage of the liquid column in the pipe lines.

I claim:

1. In an hydraulic motion transmitting system of the kind specified having means for compensating for volumetric changes of the working fluid comprising a bellows connected with each transmission line, means for maintaining the static fluid pressure in the line substantially constant comprising a link pivotally connected between a free end of said bellows and a fixed point, a spring connected under tension between a point on said link and a second fixed point, the arrangement of the spring being such that the spring exerts a torque on the link which increases as said bellows contracts.

2. In an hydraulic motion transmitting system of the kind specified having a pair of pipe lines connecting transmitter and receiver and a temperature compensating device comprising a pair of bellows connected one with each pipe line, the free ends of the said bellows being connected with opposite ends of a centrally pivoted link, and a spring under tension connected between one end of said link and a point fixed relative to the pivot of said link and so positioned that the axis of the spring moves away from the axis of the pivot of the link as the bellows contract.

3. An hydraulic movement transmitting system as claimed in claim 2 wherein the axis of the spring and the axis of the pivot intersect when the bellows are fully expanded.

4. In an hydraulic movement transmitting system of the kind specified having a pair of bellows the free ends of which are connected with opposite ends of a centrally pivoted link such that the bellows are free to expand or contract together to compensate for changes in volume of the working fluid, means for maintaining the static pressure of the fluid substantially constant comprising means for applying a force to said bellows which urge them toward their contracted position, said last-mentioned means being so arranged with respect to the pivot of said link that the force applied to said bellows increases in magnitude as the bellows contract.

5. In an hydraulic movement transmitting system of the kind specified having a pair of bellows the free ends of which are connected on opposite sides of the pivot of a centrally pivoted link, the bellows and link being arranged in such a manner that the bellows are free to expand or contract together to compensate for changes in volume of the working fluid in the system, means for applying a force to said pair of bellows tending to move the free ends thereof to a contracted position, said means comprising a spring under tension connected between one end of said pivoted link and a point fixed with reference to the pivot of said link and offset relative to the axis of the said link.

EDWARD ROKER ROBERTSON.
